US00D772522S

(12) **United States Design Patent** (10) **Patent No.:** **US D772,522 S**
(45) **Date of Patent:** **** Nov. 22, 2016**

(54) **LOCK BOX**

- (71) Applicant: **THE DRUCKER COMPANY**,
Philipsburg, PA (US)
- (72) Inventors: **Anthony J. Henderson**, State College,
PA (US); **Kenneth Moscone, Sr.**, Port
Matilda, PA (US); **Kenneth Moscone,**
Jr., Port Matilda, PA (US); **Mathew T.**
Samperi, Boxborough, MA (US); **Craig**
Stout, Port Matilda, PA (US); **Jason A.**
Stout, State College, PA (US)
- (73) Assignee: **The Drucker Company**, Philipsburg,
PA (US)

(**) Term: **15 Years**

(21) Appl. No.: **29/537,571**

(22) Filed: **Aug. 27, 2015**

(51) **LOC (10) Cl.** **99-00**

(52) **U.S. Cl.**

(57) **CLAIM**

The ornamental design for a lock box, as shown and
described.

DESCRIPTION

FIG. 1 is a top, front, left side perspective view of a lock box
showing our new design;

FIG. 2 is a front view of the lock box of FIG. 1;

FIG. 3 is a rear view of the lock box of FIG. 1;

FIG. 4 is a left side view of the lock box of FIG. 1;

FIG. 5 is a right side view of the lock box of FIG. 1;

FIG. 6 is a top view of the lock box of FIG. 1; and,

FIG. 7 is a bottom view of the lock box of FIG. 1.

The broken lines in the drawings illustrate features that form
no part of the claim.

1 Claim, 7 Drawing Sheets
